AUTOMATIC TELEPHONE SYSTEM

Eduard Wochinger, Berlin, Germany, assignor to
 Siemens & Halske Aktiengesellschaft of Wern-
 erwerk, Siemensstadt, near Berlin, Germany

Application July 22, 1937, Serial No. 154,967
 In Germany July 30, 1936

23 Claims.

(Cl. 179—26)

The invention relates to automatic telephone systems having a plurality of exchanges and in particular to such systems as have a plurality of subsidiary exchanges disposed in series with a main exchange in which calling subscribers of one exchange reach a position in another exchange serving to set up calls and in which calls to a subscriber of the calling exchange or the calling exchange group are established over connecting lines seized on the initiation of the call. It aims at utilizing the connecting line which was seized on the initiation of the call for completing the desired connection without using complicated testing circuits.

This is realized in that a connecting device in an exchange which is to be set in a desired direction is set in preparation on the connecting line seized by the calling subscriber of a preceding exchange in dependence upon the automatic setting of a connecting device of the first-mentioned exchange and, in dependence upon the direction selected by the position controlling the setting up of the call, either effects switching operations enabling the call to be established over the connecting line seized on the initiation of the call or searches for an outgoing line (connecting line or subscriber's line) in another direction.

One embodiment of the invention is represented in Figs. 1-3, Figs. 4-6 show variations in particular details.

Fig. 1 shows a diagrammatic layout in which the serially arranged subsidiary exchanges U_1 , U_2 and U_0 have access to a main exchange HA in which an operator is provided for establishing calls desired by the individual subscribers. Naturally further subsidiary exchanges can be associated with the individual subsidiary exchanges shown as is indicated for example in the case of the subsidiary exchange U_2 (to U_3). The equipment of the subsidiary exchange U_2 is shown in detail in Fig. 2 and that of the exchange U_0 in Fig. 3. The equipment of the subsidiary exchange U_1 is not shown in detail. It corresponds largely to the arrangement of the exchange U_2 with the difference that no connecting lines are associated with the call finders AS and AS_1 (Fig. 1) so that the necessary switching devices for junction traffic are omitted.

Actually only two connecting lines are shown between the subsidiary exchanges but of course a large number of connecting lines could be provided. These connecting lines branch off either directly from between the connecting links comprising call finders and final selectors of a subsidiary exchange or, as is shown in Fig. 1, for the

connecting line to the main exchange HA over secondary switches (AW), and lead to the call finders of the next subsidiary exchange. In order to make the connecting line accessible in the opposite direction it is connected in the corresponding subsidiary exchange to the contacts of the final selector which, together with the corresponding call finder, constitutes a connecting link. As shown in Fig. 2, the connecting lines which are arranged before the first group of connecting lines are once more connected to the contact bank of the final selector beyond the last group of connecting lines for special reasons which will be discussed later. The setting of the individual final selectors is effected by special setting switches which when influenced by impulses characterize the contacts on which the final selectors are to be set. In the embodiment the setting switches are associated individually with the final selectors but naturally common setting switches can be used for a plurality of final selectors.

The invention is not limited to the fact that the connecting links comprise only call finders and final selectors, other selecting stages could just as well be incorporated.

The general establishment of calls from subscriber T_{n1} of the subsidiary exchange U_1 will first be described with reference to Fig. 1.

Subscriber T_{n1} initiates a call in any desired manner and thereby causes a free call finder, for example, AS_1 , to be set on his line. If there is no call finder free the call remains registered in known manner in that the calling relay locks up. The subscriber T_{n1} is connected to the subsidiary exchange U_2 over the connecting line a_1/b_1 , after the call finder AS_1 has been set. The call initiating impulse is transmitted to this subsidiary exchange and in the event of there being a free call finder available this is thereby started up so as to take up a setting on the connecting line a_1/b_1 . In the present case the call finder AS_2 becomes set on the connecting line a_1/b_1 , and thereby on the subscriber's line T_{n1} . After the termination of the setting movement of the call finder AS_2 the calling subscriber reaches the subsidiary exchange U_0 over the connecting lines a_1/b_1 and a_0/b_0 . The call initiating impulse is received in this exchange and serves to start a free call finder (for example AS_4) hunting for the calling line. When this setting has also been completed a switch AW (secondary switch) is set in operation and this connects the calling subscriber to the main exchange HA over the connecting line a/b . Meanwhile, after the setting of the call finder AS_2 in the subsidiary exchange U_2

U₂, the final selector LW₂ has been operated and in accordance with the setting of the call finder AS₂ has automatically become set on the connecting line a₁/b₁. Similarly the final selector LW₄ in the subsidiary exchange U₀ has become set on the line a₀/b₀, seized by the call finder AS₄. The final selector LW₁ in the subsidiary exchange U₁ has not been operated since the call did not proceed over a connecting line but proceeded from a subscriber's line. The final selectors LW₂ and LW₄ also would not have become set if a subscriber had called from their associated exchanges.

After the establishment of the above connecting path a call signal is operated in the main exchange HA. Thereupon the operator in the exchange HA plugs the corresponding jack. By this means a seizing impulse is transmitted successively from subsidiary exchange to subsidiary exchange. If now the calling subscriber T_{n1} has not replaced his receiver the operator immediately receives a corresponding signal, otherwise she must recall the subscriber to his station in any desired manner which does not concern the present invention.

If subscriber T_{n1} desires a connection with subscriber T_{n4} in the subsidiary exchange U₂, the operator first transmits an impulse train whereby the setting switch (Fig. 3; EW₄) associated with the final selector LW₄ is influenced. Since the setting already taken up by the final selector LW₄ corresponds to this dialled digit the operator reaches the connecting line a₀/b₀ over the final selector LW₄. In a corresponding way the setting switch (Fig. 2; EW₂) associated with the final selector LW₂ is influenced by a further impulse train. Since in this case the setting which the final selector LW₂ has assumed does not correspond to the digit called the final selector LW₂ steps on and sets itself on the contact closed by the setting switch, i. e., on the contact associated with the desired subscriber T_{n4}. The desired subscriber is now rung in the known way. When he replies the operator withdraws the plug from the line and the connecting lines which are not used for the conversation, i. e., lines a₀/b₀ a₁ are released.

If the subscriber T_{n1} desires a call to subscriber T_{n2} of his own subsidiary exchange U₁, the calling of the operator and the preparatory setting of the final selector LW₄ in the exchange U₀ and the final selector LW₂ in the exchange U₂ take place in the same way as that just described. The setting of the setting switch (Fig. 3; EW₄) in the exchange U₀ by the impulse trains transmitted by the operator also takes place in the same way so that the operator reaches the connecting line a₀/b₀ over the final selector LW₄. The setting switch (Fig. 2; EW₂) associated with the final selector LW₂ in the exchange U₂ is now influenced by the following impulse train. Since, however, this impulse train characterizes the connecting line a₁/b₁ on which the final selector LW₂ is already standing the switch is not advanced further. Accordingly the operator reaches the connecting line a₁/b₁ seized by the calling subscriber, over this final selector. The next impulse train then causes the setting switch associated with the final selector LW₁ to be set on a contact over which the desired subscriber T_{n2} is reached. This subscriber is then called in the known way. When he replies the connecting path proceeds only within the subsidiary exchange U₁ since after the plug has been

removed by the operator all the remaining devices in the exchanges U₂ and U₀ are released.

From this general description it can be seen that by means of the preparatory setting of the final selector on the line seized when the call was initiated the establishment of the desired call by retractive selection in the calling subsidiary exchange group can take place directly over the corresponding connecting lines seized in the first place by the call.

Further details will be explained in the following detailed description of Figs. 2 and 3.

When the calling subscriber T_{n1} sets up a call in any manner (by removing the receiver, by operating a magneto, by depressing a key, etc.) the call finder AS₁ is started up in known way as has already been described with reference to Fig. 1. The call finder sets itself on the calling subscriber's line so that the calling subscriber is now connected to the subsidiary exchange U₂ over the connecting line a₁/b₁. Since battery potential has been applied to the lead a₁ (in any desired manner which does not concern the invention) after the call finder AS₁ has been set, relay A₂ is energized over this lead and contacts 1d₂, 2c₂, winding I of relay A₂ and earth. Relay A₂ locks up over: earth, battery, winding II of relay A₂, contact 14a₂, 4c₂, 5d₂ and earth. The opening of contact 3a₂ removes a short-circuit from the high resistance winding I of relay D₂ so that the line a₁/b₁ is guarded against being seized by a final selector. By the closing of contact 10a₂ relay H₂ is energized over: earth, battery, winding I of relay H₂, contacts 12p₂, 10a₂ and earth. The following circuit is completed over contact 11h₂: earth, battery, rotary magnet DAS₂, contacts 13r₂, 14das₂, 11h₂, 12p₂, 10a₂, and earth. The call finder AS₂ takes a step forward. When the rotary magnet DAS₂ of the call finder AS₂ operates contacts 14das₂ is opened so that relay R₂ is energized over: earth, battery, resistance W₁₅, relay R₂, contacts 11h₂, 12p₂, 10a₂ and earth. The opening of contact 13r₂ deenergizes the magnet DAS₂. If the calling line a₁/b₁ has not been reached the rotary magnet DAS₂ and relay R₂ mutually influence one another so as to advance the call finder AS₂ stepwise. Since however, the connecting line a₁/b₁ seized by the calling subscriber is reached on the first step taken by the call finder, the following circuit is completed: earth, battery, relay C₂, contact 15a₂, wiper as₃ of the call finder AS₂, windings I and II of relay P₂, contacts 29h₂, 30c₃ and earth. In this circuit relays C₂ and P₂ energize. At contact 16c₂ a locking circuit is completed for relay C₂ independent of contact 15a₂. The locking circuit for winding II of relay A₂ is broken by the opening of contact 4c₂ so that this relay releases. The previous guarding at contact 8a₂ is now replaced by contact 6c₂. Meanwhile relay H₂ has become deenergized through the opening of contact 12p₂ on the energizing of relay P₂ and thus the circuit for the further influencing of the rotary magnet DAS₂ and relay R₂ is broken at contacts 10a₂, 12p₂ and 11h₂. Through the disconnection of the high resistance winding II of relay P₂ the seized connecting line is guarded against seizure by another call finder. The closing of contact 40p₂ completes the following circuit: earth, battery, contacts 31sp₃ and 40p₂ lead a₀ (Fig. 3), contacts 14d₄ and 15c₄, winding I of relay A₄ and earth. In this circuit relay A₄ energizes and locks up over its winding II after closing contact 145a₄: earth, battery, winding II of relay A₄, contacts 145a₄, 71c₄ and 75

18d4 and earth. The connecting line is guarded against seizure by a final selector through the opening of contact 81a4. Meanwhile relay Sp3 in the subsidiary exchange U2 (Fig. 2) has been energized by the closing of contact 19p2. This relay by opening contact 37sp3 disconnects battery from the energizing circuit of relay A4 just described. Moreover, in the meantime, since the call finder AS2 has become set on a connecting line so that its wiper as4 rests on specially wired contacts, the following circuit is established by the closing of contact 18p2: earth, battery, relay Q2, wiper as4 of the call finder AS2 (in position 1), wiper ew3 of the setting switch EW2 (in position 0) contact 18p2 and earth. In this circuit relay Q2 energizes and at contact 54q2 completes the following circuit: earth, battery, rotary magnet DLW2 of the final selector LW2, contacts 54q2, 53h2, 52p3 and earth. The final selector LW2 steps forward one step. Since, when its magnet DLW2 was energized, winding II of relay H2 was energized over contact 65dlw2 the energizing circuit of the magnet is broken again at contact 53h2. Relay H2 and the magnet DLW2 then influence each other in turn until by way of its wiper lw5 the final selector LW2 has reached the contact seized by wiper as5 of the call finder AS2. In the present case, since the call finder AS2 stands on the first contact, the stepping of the final selector LW2 terminates after the first step for after one step the following circuit is completed: earth, battery, winding II of relay H2, wiper lw5 of the final selector LW2, wiper as5 of the call finder AS2, contact 33q2 and earth. Relay H2 remains energized in this circuit so that any further operation of the rotary magnet DLW2 is prevented by contact 53h2 being held open.

Meanwhile after relay A4 has energized the following circuit, among others, is established in the exchange U0 (Fig. 3) through the closing of contact 85a4: earth, battery, winding I of relay H4, contacts 86p4, 85a4 and earth. Relay H4 energizes so that the following circuit is completed on account of the closing of contact 87h4: earth, battery, rotary magnet DAS4 of the call finder AS4, contacts 88r4, 89das4, 37h4, 86p4, 85a4 and earth. The magnet DAS4 is energized in this circuit and advances the call finder AS4 one step. The short-circuit over relay R4 is removed by the opening of contact 89das4 so that relay R4 energizes and at contact 88r4 breaks the energizing circuit of the magnet. If the call finder AS4 has not yet reached the calling line, relay R4 and the magnet DAS4 would influence each other so as to step the call finder. Since, however, the calling line a0/b0 occurs at the first contact of the call finder AS4 the following circuit is set up after the first step taken by the switch: earth, battery, relay C4, contact 83a4, wiper as3 of the call finder AS4, windings I and II of relay P4, contacts 105h4, 106c5 and earth. Relays C4 and P4 energize in this circuit. Relay C4 locks up at contact 84c4 in a circuit independent of contact 83a4. Through the opening of contact 77c4 the locking circuit for relay A4 is broken. The guarding of the connecting line against seizure by a final selector is now effected by the opening of contact 79c4. The energizing circuit for relay H4 is broken at contact 68p4. Any further influencing of the rotary magnet DAS4 and relay R4 is thus prevented. Battery potential is connected to lead a by the closing of contact 112p4. The switch AW is accordingly started up to switch through the connecting path

to the main exchange HA and to indicate a call. If there is no such switch available the battery potential operates directly on the main exchange and switches on a call signal which is maintained. Since relay Sp5 is energized through the closing of contact 91p4 this battery potential is disconnected again at 109sp5. Meanwhile, since the call finder AS4 is resting on a connecting line and accordingly the contacts on which wiper as4 is standing are specially wired, the following circuit is completed by the closing of contact 92p4: earth, battery, relay Q4, wiper as4 of call finder AS4 in position 1, wiper ew3 of the setting switch EW4 in position 0, contact 92p4 and earth. Relay Q4 energizes in this circuit and by closing contact 133q4 energizes the rotary magnet DLW4: earth, battery, rotary magnet DLW4 of the final selector LW4, contacts 133q4, 132h4, 131p5 and earth. The final selector LW4 takes a step forward. When the rotary magnet DLW4 energizes relay H4 is operated over contact 129dlw4 so that the rotary magnet DLW4 is disconnected again by the opening of contact 132h4. The magnet DLW4 and relay H4 operate on each other until wiper lw5 of the final selector LW4 reaches the contact seized by the wiper as5 of the call finder AS4. In the present case this occurs after only one step. The following circuit is established: earth, battery, winding II of relay H4, wiper lw5 of the final selector LW4, wiper as5 of the call finder AS4, contact 113q4 and earth. Relay H4 is held energized in this circuit whereby further influencing of the rotary magnet DLW4 is prevented by the opening of contact 132h4.

At this moment the call finder AS1 (Fig. 1) in the exchange U1 is standing on the line of the calling subscriber Tn1, the call finder AS2 in exchange U2 (Fig. 2) is resting on the connecting line a1/b1 incoming from the exchange U1 and the call finder AS4 in the exchange U0 (Fig. 3) is resting on the connecting line a0/b0 incoming from the exchange U2. The exchange U0 is connected with the main exchange over the connecting line a/b. Furthermore, in the exchange U2 the final selector LW2 (Fig. 2) has been set in preparation on the connecting line a1/b1 since the associated call finder AS2 has become set on a connecting line, namely a1/b1. If a call had proceeded over another connecting line in this exchange U2 the call finder AS2 would have become set on this and then the final selector LW2 would similarly have been set in preparation on this connecting line. If, however, the call finder AS2 had been brought to rest on a subscriber's line no preparatory setting of the final selector LW2 would have occurred. This distinction in the mode of operation is produced in that the call finder contacts to which connecting lines are connected are connected together in the contact bank traversed by wiper as4 and cause the final selector LW2 to be connected up by the operation of relay Q2, the stepping of the final selector being now controlled over wiper as5 in dependence upon the setting of the call finder AS2. In the present case the final selector LW4 operates in a corresponding manner. It is also set in preparation namely upon the connecting line a0/b0. As Fig. 2 shows, the connecting lines between the exchanges U1 and U2 are repeated in the contact bank of the final selector LW2. The final selector LW2 is thus prevented from executing a complete rotation in order to reach a line to the exchange U1 according to the setting of the setting switch EW2 when the exchange U1 is characterized as the desired traffic direction in

the event of the final selector having been set in preparation on one of these connecting lines as a result of a call from the subsidiary exchange U3. This is only possible so long as the particular type of final selector admits of such repetition of the lines, otherwise the final selector must pass to the desired line across its normal position. In this case, disconnection on the eleventh step after completing the first rotary movement is prevented in that relay T2 is energized in this position so as to connect to contact 10 a disconnecting potential over its contact 66t2 which brings the switch to rest when contact 10 is reached after the second rotation.

15 A call signal is operated in the main exchange HA by the transitory connection of battery potential as already described so that the operator is notified of the call. When now the operator inserts the plug in the jack associated with the 20 connecting line *a/b*, battery is connected to the *a*-lead of this connecting line (in any manner with which we are not concerned), so that relay J4 is energized in the subsidiary exchange U0 over this lead and contacts 112p4 and 110sp5.

25 Through the closing of contact 120j4 the following circuit is set up: earth, battery, relay C5, contact 120j4 and earth. Relay C5 energizes in this circuit and locks up by closing contact 121c5. The following circuit is established by the closing 30 of contact 102j4 or 99c5: earth, battery, relay X4, contact 102j4 (in parallel with this: earth, battery, choke coil Dr1, contacts 110u4, 99c5) contacts 97k4, 94u4, 93p4, wiper *as1* of the call finder AS4 (in position 1), lead *a0* (Fig. 2), contacts 35 40p2, 38sp3, relay J2 and earth. In this circuit relay J2 energizes. Relay C3, which locks up by closing contact 48c3, energizes over contact 46j2. Through the closing of contact 34j2 or 26c3 battery potential is connected to the lead *a1* 40 of the connecting line leading to the exchange U1 over: earth, battery, relay X2, contact 34j2, (and in parallel: earth, battery, choke-coil Dr3, contacts 21u2, and 26c3), contacts 24k2, 22u2, 20p2, wiper *as1* of the call finder AS2 (in position 45 1) and lead *a1* of the connecting line of the subsidiary exchange U1. In the exchange U1 whose equipment corresponds fundamentally to that shown in Fig. 2 a relay corresponding to relay J2 is influenced by this battery potential and promotes similar switching operations. If the subscriber *Tn1* has not replaced his receiver a relay corresponding to relay Y2 (Fig. 2) is energized over the loop of the calling subscriber. Over a contact in the exchange U1 corresponding to contact 41y2 battery potential is applied to lead *b1* which energizes relay Y2 over wiper *as2* 50 of the call finder AS2 (in position 1), contacts 21p2, 23u2, 28k2, relay Y2 and earth. The closing of contact 41y2 completes the following circuit: earth, battery, choke-coil Dr4, contact 41y2, lead *b0*, (Fig. 3) wiper *as2* of the call finder AS4 (in position 1) contacts 95p4, 96u4, 101k4, relay Y4 and earth. Relay Y4 energizes in this circuit and connects battery to lead *b* leading to the 55 main exchange HA over: earth, battery, choke-coil Dr2, and contact 125y4. This operates a signal in the exchange HA which notifies the operator that the calling subscriber has waited without replacing his receiver. If the subscriber had replaced his receiver, this signal would not have been set up. The operator would then have recalled the subscriber.

70 In the present case the operator now makes her enquiry. If the calling subscriber *Tn1* of the exchange U1 wishes to set up a call to subscriber

Tn4 of the exchange U2 the operator sends back the first impulse train, comprising one impulse, over the connecting line *a/b*, i. e., she breaks the energizing circuit of relay J4 (Fig. 3). When relay J4 deenergizes the following circuit is established: earth, battery, relay V4, contacts 146c5, 119j4 and earth. In this circuit relay V4 energizes. Furthermore, the rotary magnet DEW4 receives an impulse over: earth, battery, rotary magnet DEW4, contacts 131c5, 138j4, and 139p5 10 and earth. The setting switch EW4 takes a step forward. Through the closing of contact 116dew4 when magnet DEW4 energizes relay K4 is energized and by opening contact 101k4 releases relay Y4. Relay K4 consequently locks 15 up over: earth, battery, relay K4, contacts 115k4, 114j4, wiper *ew5* of the setting switch EW4 and earth. Since relay J4 remains energised after the impulse train comprising one impulse, relay V4 deenergizes on account of the opening of contact 119j4. Since relay Q4 has held up over contact 98p4 during the time that relay V4 has been energized independently of wiper *ew3* the following circuit is established after relay V4 energizes and before relay Q4 has allowed its armature to relapse: earth, battery, winding II and I of relay D4, wiper 1w3 of the final selector LW4, windings I and II of relay P5, contacts 124p4 and 128q4, wiper *lw4* of the final selector LW4 (in position 1), wiper *ew1* of the setting 20 switch EW4 (in position 1) contact 143c5, earth. Relay P5 which has been primed over its winding III between the contact 128q4 energizes and causes relay U4 to energize over contact 142p5 before relay Q4 deenergizes, relay U4 locking up 25 over: earth, battery, relay U4, contacts 140u4, 142p5, 143c5 and earth. Any stepping of the final selector LW4 is prevented by the opening of contact 131p5 since the preliminary setting of the final selector corresponds to the setting of the 30 setting switch EW4. Relay H4 is deenergized by the opening of contact 113q4. Through the opening of contacts 122p5 and 123p5 the leads *a* and *b* of the connecting line incoming to the main exchange HA are switched through to the 35 leads *a0/b0*. At contact 126p5 the connecting line which has been reached and which corresponds to the connecting line *a0/b0* seized on the initiation of the call is guarded. The final selector LW4 is disconnected from the call finder AS4 40 at contacts 94u4 and 96u4. Relay Y4 is now energized again over: (Fig. 2) earth, battery, choke-coil DR4, contact 41y2, lead *b0*, (Fig. 3) wiper *lw2* of the final selector LW4 (in position 1), contact 123p5, relay Y4 and earth.

The operator transmits five impulses to form the second impulse train since it is subscriber Tn4 of the exchange U2 who is wanted. Accordingly the energizing circuit of relay J4 is broken 5 times. Consequently, the following circuit is broken 5 times at contact 102j4, earth, battery, relay X4, contacts 102j4 and 122p5, wiper *lw1* of the final selector LW4 (in position 1), lead *a0* (Fig. 2), contacts 40p2 and 38sp3, relay J2 and earth. When relay J2 deenergizes for the 55 first time relay V2 is energized over: earth, battery, relay V2, contacts 141c3 and 47j2 and earth. Furthermore, the rotary magnet DEW2 is operated over: earth, battery, rotary magnet DEW2, of the setting switch EW2, contacts 63c3, 58j2, and 52p3 and earth. The setting switch EW2 is accordingly displaced 5 steps. When the rotary magnet DEW2 of the switch EW2 energized for the first time relay K2 was energized over: earth, battery, relay K2, contacts 49dew2, 70

and 48c3 and earth. It holds up after relay Y2 has deenergized on the opening of contact 28k2 over: earth, battery, relay K2, contacts 45k2, 44y2, wiper ew5 and earth. At the end of the impulse train (relay J2 remains energized) relay V2 releases on account of the opening of contact 47j2. After some time relay Q2 also deenergizes on account of the opening of contact 17v2. No circuit can be established for relay P3 since the preliminary setting of the final selector LW2 does not correspond to the setting of the setting switch EW2. Instead the following circuit is set up: earth, battery, rotary magnet DLW2, wiper lw6 on the contact segment, contacts 53h2 and 52p3 and earth. In this circuit the magnet DLW2 is operated under the control of relay H2 until wiper lw4 reaches the contact characterized by wiper ew1 of the setting switch EW2 (this rests on the 5th contact). The relay P3 is then influenced over the testing lead of the subscriber Tn4 wiper lw3 of the final selector LW2, winding I of relay P3, contact 61q2, wiper lw4 of the final selector LW2, wiper ew1 of the setting switch EW2 (in position 5), contact 71c3 and earth. Relay P3 by opening contact 52p3 prevents any further advance of the final selector LW2 which now rests on the desired subscriber's line (Tn4). The subscriber Tn4 is called in any desired manner either by special switching measures taken by the operator in the main exchange HA or by the automatic transmission of ringing current in the exchange U2. When the wanted subscriber replies relay Y2 energizes over the loop established. The operator receives a signal by way of contact 41y2. Through the opening of contact 48y2 the locking circuit of relay K2 is broken so that a communication is established between the calling subscriber Tn2 and subscriber Tn4 over call finder AS1 in the exchange U1, the connecting line a1/b1, the call finder AS2 in the exchange U2 and the final selector LW2.

After receiving the called party's reply signal the operator withdraws the plug from the jack in the main exchange HA. Relay J4 (Fig. 3) in the subsidiary exchange U0 consequently deenergizes. Relay C5 is deenergized through the closing of contacts 117j4 and 118x4 because relay X4 releases on the opening of contact 102j4. The opening of contact 107c5 deenergizes relay P4 and the opening of contact 91p4 deenergizes relay S5. Relay C4 is also deenergized. Relay P5 deenergizes through the opening of its locking circuit passing over winding III and contact 148p5 at contact 143c5. The magnet DLW4 of the final selector LW4 is switched on over contact 131p5 so that the final selector LW4 restores to normal under the control of relay H4. When the normal position is reached the rotary magnet DEW2 is switched on over wiper lw6 so that this switch also restores to normal under the control of relay H4. Meanwhile the circuit for relay J2 in the exchange U2 has been broken through the breaking of contact 102j4 when relay J4 deenergizes so that relay J2 releases. Since, however, relay Y2 is now energized over the loop of subscriber Tn4 as already mentioned, and thus relay X2 is held over this loop, relay C3 cannot be short-circuited and remains energized so that the call finder AS2 and the final selector LW2 remain set. The connection now exists between subscriber Tn1 in the exchange U1 and subscriber Tn4 in the exchange U2. Any seizure of the assembly consisting of the call finder AS2 and the final selector LW2 over the connecting line a0/b3 is prevented by the following circuit: earth, bat-

tery, choke-coil DR4, contact 41y2, lead b0, (Fig. 3) relay Sp4, contacts 76a4, 77c4, 78d4 and earth. The high resistance winding I of relay D4 is switched on at contact 62sp4 so that the line is guarded.

5

Establishment of a call to subscriber Tn2 of the same subsidiary exchange

If subscriber Tn1 desires to call subscriber Tn2 of his own subsidiary exchange U1, the operator, after having been reached by the subscriber in the same way as described above, transmits the first impulse train comprising one impulse as before so that the operator gains access to the connecting line a0/b0 over the final selector LW4 15 in the manner set out above. In order to set the setting switch EW2 in the exchange U2 the operator now transmits a second impulse train also consisting of one impulse. Relay J2 (Fig. 2) is thereby deenergized once. In addition to the 20 energizing of relay V2 over 47j2 and 47c3 the rotary magnet DEW2 is energized once over contacts 52p3, 58j2 and 63c3 so that the setting switch EW2 is set on the first contact. Since now wiper ew1 of the setting switch EW2 rests on the same 25 contact as does wiper lw4 of the final selector LW2, the following circuit is set up after relay V2 is deenergized at the end of the impulse train since relay Q2 remains up over contact 17v2 and is held in this condition on account of its slow- 30 to-release feature: earth, battery, windings II and I of relay D2, wiper lw3 of the final selector LW2 (in position 1), windings I and II of relay P3 (pre-energized over winding III), contacts 59v2 and 62q2, wiper lw4 of the final selector LW2 35 (in position 1), wiper ew1 of the setting switch EW2 (in position 1), contact 71c3 and earth. In this circuit relays D2 and P3 energize closing contact 70p3. Relay U2 is energized before contact 13q2 opens, over: earth, battery, relay U2, 40 contacts 13q2, 18p3 and 11c3 and earth. Relay U2 locks up at contact 72u2 in a circuit independent of contact 72q2. On the energizing of magnet DEW2 relay K2 was energized over contact 49dew2; it locked up after relay Y2 had been de- 45 energized by the opening of contact 28k2, in a circuit over: earth, battery, relay K2, contacts 45k2 and 44y2, wiper ew5 and earth. Through the energizing of relay U2 the wipers as1 and as2 of the call finder AS2 are disconnected at contacts 22u2 and 23u2. The relay J in the subsidiary exchange U1 corresponding to relay J2 is held energized over: earth, battery, relay X2, contacts 34j2 and 42p3, wiper lw1 of the final selector LW2 (in position 1) lead a1 to the subsidiary exchange U1, since contacts 42p3 and 63p3 are now closed.

The next impulse train transmitted by the operator is received by relay J4 in the subsidiary exchange U0 and by relay J2 in the exchange U2 60 and is from there transmitted to the corresponding relay in the exchange U1. In this exchange the final selector LW1 is set in the known way, in the present case on the line of the wanted subscriber Tn2. In the event of this subscriber 65 being free, ringing current is transmitted in the known way so that when the subscriber Tn2 replies the corresponding X and Y relays operate and indicate the reply to the operator.

The operator thereupon withdraws the plug in 70 the exchange HA. The call finder AS4 and final selector LW4 in the exchange U0 are thereby released in the manner described in the case of the preceding call. Since now the relay J2 in the subsidiary exchange U2 is already deener- 75

gized on this release through the opening of the lead a_0 the call finder AS2 and the final selector LW2 in the exchange U2 also commence to release. Actually relay C3 is deenergized by the closing of contact 50j2 and contact 51x2 since relay X2 is also deenergized by the opening of contact 34j2.

Through the opening of contact 71c3 relay U2 is deenergized. Similarly relay P3 (locking circuit over contact 148p3 and winding III) is disconnected by the opening of contact 71c3 so that the following circuit arises: earth, battery, rotary magnet DLW2 of the first selector LW2, wiper lw_6 on the contact segment, contacts 53h2 and 52p3 and earth. Relay H2 is switched in for the purpose of advancing the final selector LW2 in the manner already described so that through the reciprocal control between this relay and the rotary magnet the final selector LW2 is restored to normal. When wiper lw_6 returns to normal the following circuit is set up: earth, battery, magnet DEW2, contact 51c3, wiper ew_4 on the contact segment, wiper lw_6 in the rest position, contacts 53h2 and 52p3 and earth. This magnet 25 also is operated under the control of relay H2 until the setting switch EW2 is restored to normal.

In the call finder AS2 relay P2 is released through the opening of contact 31c3 so that now 30 the line between the call finder AS2 and the final selector LW2 is broken at contacts 20p2 and 21p2 and 42p3 and 43p3. The connecting devices in the subsidiary exchange U2 are now restored to normal. Since as already mentioned a relay corresponding to relay Y2 (Fig. 2) is energized when subscriber Tn_2 in the exchange U1 replies, i. e., since a contact corresponding to contact 41y2 is closed, relay Sp2 in the exchange U2 is energised as was described in connection with relay Sp4 in the preceding call. The line a_1/b_1 is thus 35 guarded against any seizure (opening of contact 9sp2).

The call between subscribers Tn_1 and Tn_2 now proceeds entirely within the exchange U1. All 40 the other connecting paths are released.

Fig. 4 shows a modification of the starting circuit for the final selector LW4 which of course can also be applied to the final selector LW2. In place of winding II of relay H4 a special relay H5 is provided. Moreover, a contact 150h4 is provided in parallel with contact 92p4 and the starting position of the call finder AS4 is wired to the contacts for the connecting lines. When a call comes in relay Q4 is influenced over contact 55 150h4 together with the call finder AS4 the wipers of the latter being accordingly set so that the final selector LW4 is immediately set in operation and does not wait until after the call finder AS4 has been set as in the preceding example. The controlling and stopping of the final selector LW4 is then effected by relay H5 in that a contact 132h5 is provided in place of contact 132h4 (Fig. 3).

If the final selector LW4 is required to start up 60 only on the reply of the operator the circuit is modified as shown in Fig. 5. In this case a contact of relay J4 is disposed in the energizing circuit of relay Q4, the former relay being energized as usual on the reply of the operator and accordingly only operating relay Q4 over its contact 65 150j4 at this moment, the final selector LW4 only then being started up. Naturally this modification can also be applied to the final selector LW2.

Fig. 6 shows a modification whereby the final 70 selector LW4 only commences to operate when

the operator sends back impulses. As may be seen from this figure, in which only those circuit details are shown which differ from the arrangement shown in Fig. 3, relay V4 is energized by contact 119j4 on the first impulse over the closed contact 146c5. Since now relay Q4 is energized over contacts 92p4, 151c5, and 90v4 the final selector is advanced under the control of relay H4 on account of the closing of contact 133q4 (Fig. 3) in the manner described above until it reaches the line seized by the call finder AS4 and is brought to rest on this line as has already been described in connection with Fig. 3. Relay V4 remains up during the stepping of the final selector LW4 over contacts 154h4, 153q4 and 152v4 since it is slow-to-release.

In a similar way the setting of the final selector LW2 and any other final selectors present may be altered so that in the subsidiary exchange in which impulses are received from the operator the final selector in this exchange is only given a preparatory setting when these impulses are received in the event of the associated call finder standing on a connecting line (relay Q).

What is claimed is:

1. In a switching system serving a plurality of lines, a finder switch, a connector switch, means responsive to a call over any of said lines for causing said finder to seize the calling line and extend it to said connector and also for causing said connector to set its wipers upon said calling line, means for characterizing in said connector any of said lines to which it is desired that said connector shall extend a connection, said connector effective responsive to said characterization if the line with which said wipers are associated is so characterized to complete a connection to that line regardless of its condition or, alternatively, if the line with which said wipers are associated is not so characterized to move said wipers to said characterized line and complete a connection thereto if said characterized line is idle.

2. In a switching system serving a plurality of lines, a line finder switch, a connector switch, said finder effective responsive to a call over any of said lines to seize the calling line and to extend it to said connector, a control line, said connector effective responsive to seizure of said control line to set its wipers upon said calling line, means controllable over said control line for characterizing in said connector any of said lines to which it is desired that said connector shall extend a connection, said connector effective responsive to said characterization if the line with which said wipers are associated is so characterized to complete a connection to that line regardless of its condition or, alternatively, if the line with which said wipers are associated is not so characterized to move said wipers to said characterized line and complete a connection thereto if said characterized line is idle.

3. In a switching system serving a plurality of lines, a line finder switch, a connector switch, said finder effective responsive to a call over any of said lines to seize the calling line and extend it to said connector, a characterizing switch, a control line, said characterizing switch effective responsive to impulses received over said control line to mark in said connector any of said plurality of lines to which it is desired that said connector shall extend a connection, said connector effective responsive to the initiation of said impulses over said control line to set its wipers upon said calling line and effective respon-

sive to the completion of said marking if the line with which said wipers are associated is so marked to complete a connection to that line regardless of its condition or, alternatively, if the line with which said wipers are associated is not so marked to move said wipers to said marked line and extend a connection thereto if said marked line is idle.

4. In a switching system, a plurality of lines, connecting means having access to said lines, means for seizing said connecting means over any of said lines and for characterizing the seizing line in said connecting means, said connecting means effective to extend an incomplete preliminary connection to said seizing line in accordance with said characterization, means for characterizing, in said connecting means, any one of said lines to which it is desired said connecting means shall complete a connection, means in said connecting means effective only if the line which is desired according to last said characterization is the line to which said preliminary connection has been extended for causing said connection to be completed to said desired line regardless of its condition, last said means effective if the line which is desired according to last said characterization is some line other than the line to which said preliminary connection is extended for causing said preliminary connection to be abandoned and a connection to be completed to said desired line only if said desired line is idle.

5. In a switching control system, a plurality of lines extending to each of a plurality of stations, connecting means having access to said lines, means for seizing said connecting means over any of said lines and for characterizing the seizing line in said connecting means, said connecting means effective to extend an incomplete preliminary connection to said seizing line in accordance with said characterization, means for characterizing, in said connecting means, any one of said stations to which it is desired said connecting means shall complete a connection, means effective only if the desired station according to last said characterization is the station to which said seizing line extends for causing said connecting means to complete said preliminary connection to said seizing line regardless of its condition, said last means effective if the desired station according to last said characterization is some station other than the station to which said seizing line extends for causing said connecting means to abandon said preliminary connection and to complete a connection to an idle one of said plurality of lines extending to said desired station if one is available.

6. In a switching control system, a plurality of lines extending to each of a plurality of primary stations, a line extending to each of a plurality of secondary stations, connecting means having access to said lines, means for seizing said connecting means over any of said lines, last said means effective only if the seizing line is from a primary station to characterize said seizing line in said connecting means, said connecting means effective to extend an incomplete preliminary connection to said seizing line in accordance with said characterization if said seizing line is from a primary station, means for characterizing, in said connecting means, any of said stations to which it is desired said connecting means shall complete a connection, means effective only if the desired station is both the station to which said seizing line extends and is also

a primary station for causing said connecting means to complete said preliminary connection to said seizing line regardless of its condition, last said means effective when the desired station is either a secondary station or a primary station to which said seizing line does not extend for causing said connecting device to abandon said preliminary connection and to complete a connection to the desired station only if an idle line to said desired station is available.

7. In a switching control system, a plurality of groups of lines, an automatic switch having access to said lines, means for seizing said switch over any of said lines, means for automatically presetting the wipers of said switch upon the line by which said switch was seized, means for characterizing the lines of any of said groups in said switch, means for moving said wipers from their preset position in search for an idle characterized line and, if one is found, for completing a connection over said wipers to said line, last said means effective only if the line upon which said wipers are preset is characterized to complete a connection over said wipers in their preset position to said line regardless of its condition.

8. In a switching control system, a plurality of lines, an automatic switch having access to said lines, means for seizing said switch over any of said lines, means effective at times for automatically presetting the wipers of said switch upon the line by which said switch was seized, means for characterizing any of said lines in said switch, means responsive to said characterization for moving said wipers to the characterized line, means for determining the condition of the characterized line and for completing a connection thereto over said wipers if said characterized line is idle, last said means effective only if said wipers are preset and if the line upon which said wipers are preset is characterized to complete a connection thereto over said wipers in their preset position regardless of the condition of the line.

9. In a telephone system, an automatic switch, a plurality of groups of lines accessible to the wipers of said switch, means responsive to a call over any one of said lines for extending the calling line to said switch and for marking said calling line in said switch, means in said switch for causing its wipers to be associated with said calling line in accordance with said marking, a control position, means for associating said position with said switch, means controllable at said position for characterizing all of the lines of any of said groups in said switch, means in said switch for completing a connection from said position to said calling line over said wipers if said calling line is one of the characterized lines, or, alternatively, if said calling line is not one of the characterized lines, for causing the wipers to be moved in search for an idle characterized line and, if one is found, for causing a joint connection from the calling line and said position to be extended over said wipers to said idle characterized line.

10. In a telephone system, an automatic switch, a plurality of lines accessible to the wipers of said switch, means responsive to a call over any one of said lines for extending the calling line to said switch, last said means also effective at times to mark said calling line in said switch, means in said switch for causing its wipers to be associated with said calling line in accordance with said marking if said calling line is

so marked, a control position, means for associating said position with said switch, means controllable at said position for characterizing any of said lines in said switch, means in said switch, effective if said wipers are associated with said calling line and said calling line is so characterized, for completing a connection over said wipers from said position to said calling line responsive to said characterization or, alternatively, if said wipers are not associated with said calling line or said calling line is not so characterized, for moving said wipers to said characterized line and for extending a joint connection from said calling line and said position to said characterized line if said characterized line is idle.

11. In a switch for completing a connection to any line of a plurality of groups of lines, a control line, means responsive to seizure of said switch by any one line of said plurality of groups of lines for completing a connection from said one line to said control line, means for automatically pre-setting the wipers of said switch upon said one line, means controllable over said control line for characterizing the lines of any of said groups in the bank of said switch, means effective upon completion of said characterization for moving said wipers from their preset position to search for an idle one of said characterized lines and, if one is found, to cause a joint connection from said one line and said control line to be extended over said wipers to said idle characterized line, last said means effective only if said one line is characterized by said characterization to interrupt the original connection from said one line to said control line and to complete a connection from said control line to said one line over said wipers in their preset position.

12. In a switch for completing a connection to any of a plurality of lines, a control line, means responsive to seizure of said switch by any one of said plurality of lines for completing a connection from said one line to said control line, means effective at times for automatically pre-setting the wipers of said switch upon said one line, means controllable over said control line for characterizing any of said plurality of lines in the bank of said switch, means effective upon completion of said characterization for moving said wipers to a final setting upon the characterized line and for completing a joint connection thereto from said one line and said control line if said characterized line is idle, last said means effective only if the characterized line is said one line and said wipers are preset upon said one line to interrupt the original connection from said one line to said control line and to complete a connection from said control line to said one line over said wipers in their preset position.

13. In a switching center, an automatic switch for completing a connection to any lines of a plurality of groups of lines, a characterizing switch associated with said automatic switch, a control position, means for seizing said automatic switch over any of said lines, means responsive to said seizure for extending the seizing line to said control position, means for automatically setting the wipers of said automatic switch upon said seizing line, means controllable at said position for operating said characterizing switch to mark the lines of any of said groups in the bank of said automatic switch, means effective if the line with which said wipers are associated is one of the marked lines for causing a connection to be completed over said wipers from said control line to said line with which said wipers

are associated, or alternatively, if the line with which said wipers are associated is not one of the marked lines, for causing said wipers to be moved in search for an idle marked line and, if one is found, for causing a joint connection to be extended thereto from said seizing line and said control position.

14. In combination, a plurality of lines, an automatic switch having access to said lines, means for seizing said switch over any of said plurality of lines, switching means in said switch, means effective at times for causing the wipers of said switch to be associated with said seizing line and for preparing a primary operating circuit for said switching means, means for placing a potential in the bank of said switch upon any of said plurality of lines to which it is desired that said switch shall extend a connection, said potential effective if placed upon said seizing line and if said wipers are associated with said seizing line to operate said switching means in said primary circuit to complete a connection over said wipers to said seizing line, said third means effective if said switching means is not operated in said primary circuit responsive to the placing of said potential upon the desired line to cause a secondary operating circuit for said switching means to be effective and to cause said wipers to be moved in search for said desired line, said potential effective when said wipers are associated with said desired line to operate said switching means in said secondary circuit only if said desired line is idle to thereby complete said connection over said wipers to said desired line.

15. In a combination as claimed in claim 14, wherein busy lines are marked in the bank of said switch, and wherein said switching means tests, in said secondary circuit only, the condition of lines encountered by said wipers in said search for said desired line to prevent the completion of said connection to a desired line which is busy.

16. In a link circuit serving a plurality of lines, a finder switch, a connector switch, a control line, means responsive to seizure of any of said plurality of lines for causing said finder to extend a connection from the seized line to said control line and to mark said seized line in the bank of said connector, switching means in said connector, means for causing the wipers of said connector to be associated with said seized line in accordance with said marking and for preparing a primary operating circuit for said switching means, means controllable over said control line for placing a potential in the bank of said connector upon any of said plurality of lines to which it is desired that said connector shall extend a connection, said potential effective if placed upon said seized line to operate said switching means in said primary circuit to complete a joint connection from said seized line and said control line over said wipers to said seized line, said third means effective if said potential is not placed upon said seized line to both break said primary circuit for said switching means and prepare a secondary operating circuit for said switching means and also to cause said wipers to be moved in search for said desired line, said potential effective when said wipers are associated with said desired line to operate said switching means in said secondary circuit only if said desired line is idle to thereby complete said joint connection from said seized line and said control line over said wipers to said desired line.

17. In a link circuit such as claimed in claim 16, means for breaking the connection extended from said seized line to said control line by said finder, wherein said third means renders last said means responsive to the operation, in said primary circuit only, of said switching means.

18. In a switching control system, a plurality of lines, an automatic switch having access to said lines over its wipers, means for seizing said switch over any of said lines, means responsive to said seizure for marking the seizing line in the bank of said switch, means for presetting the wipers of said switch upon said seizing line in accordance with said marking, means for marking, in the bank of said switch, any one of said lines to which it is desired that said switch shall extend a connection, a test relay in said switch for determining the condition of lines encountered by the wipers of said switch and for seizing a line which is desired according to last said marking if said desired line is idle, means effective only if the line upon which said wipers are preset is the line which is desired according to last said marking for causing said relay to complete a connection over said wipers to said desired line regardless of its condition.

19. In a switching control system, a plurality of lines, an automatic switch having access to said lines over its wipers, means for seizing said switch over any of said lines, means responsive to said seizure for marking the seizing line in the bank of said switch, means for marking, in the bank of said switch, any one of said lines to which it is desired said switch shall extend a connection to thereby direct the wipers of said switch to a setting upon the desired line, a test relay in said switch for determining the condition of lines encountered by the wipers of said switch and for seizing the line which is desired according to last said marking if said desired line is idle, means effective only if the same line which is marked as the desired line is also marked as the seizing line for causing said relay to complete a connection to that line over said wipers regardless of its condition.

20. In a switching system, a plurality of lines, an automatic switch having access to said lines, means for marking busy ones of said lines in one bank of said switch, a relay in said switch for testing simultaneously both said one bank and also another bank of said switch over the wipers

of said switch and for extending a connection to any of said lines with which said wipers are associated if that line is both idle and is also marked in said other bank, means for seizing said switch over any of said lines, means for setting said wipers upon one of said lines and for preparing a special circuit to said relay to cause said relay to extend a connection to said one line regardless of its condition if said one line is marked in said other bank, means for marking in said other bank any of said lines to which it is desired said switch shall extend a connection, means effective only if said one line is not so marked in said other bank for causing said special circuit to be broken and to cause said wipers to be moved under control of said relay in search for a line so marked.

21. In a switching system such as claimed in claim 20, wherein said second means marks the seizing line in said switch, and wherein said third means sets said wipers upon said seizing line in accordance with last said marking.

22. In a switching control system, a plurality of lines, an automatic switch having access to said lines over its wipers, a relay in said switch for determining the condition of lines encountered by said wipers and for completing connections over said wipers to idle lines only, means for seizing said switch, means for presetting its wipers upon one of said lines, a variably operable register for characterizing any of said lines upon which it is desired that said wipers shall be finally set, and means effective only if the line upon which said switch is preset is so characterized for causing said relay to complete a connection over said wipers to that line regardless of its condition.

23. In a switching system, a plurality of lines, a connector having access to said lines, means for seizing said connector over any of said lines, means in said connector operated to prepare a connection to the seizing line, a register operated to characterize any one of said lines, and means in said connector for completing said prepared connection to the seizing line if it is the line characterized by said register, or, if some other line is so characterized, for abandoning said prepared connection and completing a connection to the characterized line only if said characterized line is idle.

EDUARD WOCHINGER.
